UNITED STATES PATENT OFFICE.

ALEXUS C. LINDGREN, OF MOLINE, ILLINOIS, ASSIGNOR TO MOLINE PLOW COMPANY, A CORPORATION OF ILLINOIS.

CULTIVATOR.

1,106,722.

Specification of Letters Patent. Patented Aug. 11, 1914.

Application filed March 3, 1913. Serial No. 751,768.

To all whom it may concern:

Be it known that I, ALEXUS C. LINDGREN, a citizen of the United States, residing at Moline, in the county of Rock Island and State of Illinois, have invented certain new and useful Improvements in Cultivators, of which the following is a specification, reference being had therein to the accompanying drawing.

10 This invention relates to cultivators, and has reference more particularly to two-row wheeled cultivators. Cultivators of this type are usually equipped with two draft tongues and are drawn by four horses, two 15 each at the outer sides of the tongues. In consequence it is necessary to employ a draft equalizer which is of considerable length, and which is hitched high in order to straddle the rows at the outer sides of the wheels. 20 An equalizer thus hitched, while possessing the advantage of avoiding or straddling the rows of plants, is objectionable in the respect that it produces decided neck weight on the draft animals. To avoid this neck 25 weight, it has been customary to employ a tongue truck consisting usually of one or two swiveling wheels so connected to the machine as to give support to the tongue, and in this manner prevent the weight from 30 coming on the horses' necks. This expedient has also been found to be objectionable when the machine is turned at the ends of the rows, or when the machine is backed up as most farmers do; after making the turn, the 35 wheels of the truck in such operations assuming bad obstructing positions, and frequently being twisted out of shape.

It is the aim of the present invention to avoid these objections attendant upon the 40 use of tongue trucks, and the invention consists in so connecting the truck to the machine that it may be moved or shifted from its supporting, operative position to an inoperative position where it will not interfere with the turning or backing or other movements of the machine.

More specifically, the invention consists in securing the truck to the machine so that it may be raised clear of the ground, and in 45 providing a lever mechanism within reach of the driver, by means of which the truck may be elevated when the machine is turned or backed, so as not to interfere with these movements. Inasmuch as the neck weight 50 of the tongue on the team is only felt when

the team is pulling with the cultivating tools in action in the ground, which conditions do not obtain when the machine is being turned or backed, it is manifest that the tongue needs no support at such times; hence I am 60 enabled by my improved construction to secure all the advantages of a high hitch, and at the same time avoid all the objections of a tongue-supporting truck.

In the accompanying drawings I have 65 shown my invention embodied in the form which at the present time I deem the most suitable for realizing the objects and advantages sought, but it will be understood that the construction may be variously 70 changed and modified within the skill of the mechanic without departing from the limits of my invention; and further, it will be understood that the invention is not limited to any particular form or construction of 75 the parts, except in so far as such limitations are specified in the claims.

In the accompanying drawings: Figure 1 is a top plan view of a two-row cultivator, having my invention embodied therein; Fig. 80 2 is a side elevation of the same, with the tongue-supporting truck in its lowered operative, supporting position, as it appears when the machine is being drawn through the field with the cultivating tools in operation; and Fig. 3 is a similar view showing the supporting truck raised from the ground to an inoperative position.

Referring to the drawings, 1 represents the frame of a two-row cultivator, which 90 frame comprises a transverse frame-bar 2, to the ends of which carrying-wheels 3—3 are connected, preferably in such manner that they may swivel or rock on vertical axes in order to enable the machine to be 95 accurately guided in following deviations in the rows of plants. This frame-bar has the rear ends of two draft tongues 4—4 connected fixedly to it, which tongues extend forwardly and are suitably braced to the 100 frame-bar by means of diagonally-extending braces 5, 5 and 6, 6, connected at their forward ends to the opposite sides of the tongues, respectively, and connected at their rear ends to the transverse frame-bar. The 105 transverse frame member with the two tongues fixedly connected thereto, as described, constitutes in effect a rigid cultivator-frame, which frame gives support to suitable cultivator beams 7, 7, etc., equipped 110

with the usual cultivating tools. A short distance in advance of the transverse frame member, a long transverse bar 8 is provided, which is fixedly connected to the two tongues 5 and carries idler pulleys 9, 9 on its ends, around which an evener chain 10 passes, and has connected with its opposite ends double trees 11, 11, each equipped with two swingle trees 12, 12, for the attachment of 10 the draft animals.

14 represents a tongue-supporting truck, in the present instance comprising two wheels 15, 15, mounted on the ends of a transverse axle 16 having fixed to it between 15 its ends a fore and aft extending collar 17 containing in its side a circumferential slot 18. Within this collar is loosely mounted the rear end of a horizontal fore and aft extending stem 19, which is confined in the 20 collar by means of a pin 20 extending outwardly from the side of the stem and through the slot 18, this arrangement limiting the rocking movement of the axle and 25 wheels on the stem. At its forward end the stem is provided with a vertical stud 24, mounted to swivel in a vertical bearing opening in a bracket member 22, which bracket member is formed with a rearward extension 23, having depending stops 24 at 30 its ends adapted to be engaged by the stem 19 and limit the motion of the same as it swings back and forth horizontally around the vertical axis of the stud. The bracket member has rigidly fixed to its opposite sides 35 the rear ends of hanger bars 25, 25, which bars extend forwardly, upwardly and outwardly, and have their forward ends pivoted by means of horizontal transverse pivot pins 26, 26, to fixed lugs 27, 27, depending from 40 the under side of a bar 28 fixedly connected to the under sides of the two tongues some distance in advance of the long bar 8 before alluded to. At its rear end the bracket member 22 has connected rigidly with it the 45 forward end of a fore and aft extending bar 29, which extends rearwardly and upwardly and is pivoted at its rear end between the rear ends of two brace bars 30, 30, extending forwardly with their forward 50 ends pivoted as at 31, 31, to the hanger bars 25, 25, respectively, adjacent the point of connection of these hanger bars with the lugs 27.

From the construction described it will 55 be seen that the supporting truck is located some distance in advance of the carrying wheels of the cultivator, and is so connected with the cultivator-frame that it will give support to the draft tongue, while at the 60 same time it is capable of a vertical movement with reference to the frame.

A vertical link 32 is pivoted at its lower end at the junction of the brace bars 30 with the bar 29, and is pivoted at its upper end, as at 65 32', to the lower end of a hand lever 33,

pivotedly mounted, as at 34, on a standard 35 rigidly connected with the frame of the machine, the said hand lever being provided with the usual locking dog 36 adapted to engage in notches 37, 37, in a segment frame 70 38 connected with the standard 35.

From the construction described, it will be seen that the tongue truck is connected with the frame of the machine at a point where it will give support to the tongue as the 75 truck travels over the surface of the ground in the position shown in Fig. 2. Further, it will be seen that the truck may be elevated bodily free of the surface of the ground by means of the hand lever mechanism, and 80 locked in an elevated position, as shown in Fig. 3. When the cultivator is in action, with the cultivating tools in the ground and the machine being drawn by the draft animals, the truck is locked down in operative 85 supporting position by means of the hand lever and its connections, as shown in Fig. 2, and in this position it will prevent the draft on the evener mechanism from causing the neck weight of the tongues to be imposed on the draft animals. When the end 90 of the row being cultivated is reached and the team is turned, the strain on the frame being relieved, the tendency to neck weight is also relieved and the driver, by unlatching the hand lever and drawing the same toward him, may lift the truck bodily upward to an inoperative position free of the surface of the ground, as shown in Fig. 3. This will enable the team to be turned 100 freely without obstruction, and also will enable the same to be backed up in starting on the new row, without obstruction being offered by the truck. In starting down the second row, the hand lever is again unlocked 105 and pushed forwardly, with the result that the truck will be lowered to its former operative supporting position, in which position it will sustain the tongues and prevent the neck weight from being imposed.

In the operation of the machine with the tongue truck in its lower supporting position, the latter, due to its swiveling action, will act as a caster wheel and hence will not interfere with the accurate guiding of the 115 cultivator-frame, which in the present instance is accomplished by the manipulation of the swiveling carrier wheels before alluded to.

It will be manifest that while I have 120 shown my invention as applied in connection with a special form of two-row cultivator, the invention is applicable as well to other forms of cultivators and like machines, the essence of the invention residing in the provision of a supporting device or truck adapted, when the machine is in normal operation, to support the draft tongue or device so as to relieve the neck weight on the draft animals, and adapted to be moved from its sup- 125 130

porting position to an inoperative position where it will not interfere with the turning or backing or like movements of the machine.

Having thus described my invention, what

5 I claim is:—

1. In an agricultural machine, the combination of a wheeled frame, a draft tongue extending forwardly therefrom, a supporting device connected thereto and adapted 10 when the machine is in operation to travel along the ground and give support to the said draft tongue, said supporting device being movable relatively to said tongue and frame to inoperative non-supporting position when the machine is out of operation, and means for controlling the movements of 15 said supporting device.

2. In an agricultural machine, the combination of a wheeled frame, a draft tongue 20 extending forwardly therefrom, a wheeled truck connected thereto and adapted, when the machine is in operation, to give support to the draft tongue, said truck being movable upwardly relatively to said tongue and frame to inoperative non-supporting position when the machine is out of operation, and means for controlling the movements of 25 said truck.

3. In an agricultural machine, the combination of a wheeled frame, a draft tongue 30 extending forwardly therefrom, a wheeled truck connected thereto in position to give support to the tongue when the machine is in operation, said truck being freely movable about an upright axis situated in advance of the axis of its wheels, and means for moving said truck relatively to the frame and tongue to an inoperative non-supporting position, when the machine is 35 out of operation.

4. In an agricultural machine, the combination of a wheeled frame, a draft tongue 40 extending forwardly therefrom, a swiveling truck connected thereto and adapted to give support to the tongue when the machine is 45

in operation, said truck being movable relatively to the frame and tongue up and down, and means for controlling the up and down movements of said truck.

5. In an agricultural machine, the combination of a wheeled frame, a draft tongue 50 extending forwardly therefrom, a wheeled truck connected thereto and movable up and down relatively to the tongue and frame about an axis situated in advance of the axis 55 of the truck wheels, and means for controlling the up and down movements of said truck.

6. In an agricultural machine, the combination of a wheeled frame, a draft tongue 60 extending forwardly therefrom, a tongue supporting device adapted to travel along the ground and give support to the tongue, hanger bars connected at their rear ends with said supporting device and pivoted at 65 their forward ends to the draft tongue, whereby the said supporting device is movable up and down relatively to the tongue and frame, a lever mechanism on the frame, and connections between the lever mechanism 70 and the supporting device.

7. In an agricultural machine, the combination of a wheeled frame, two draft tongues connected rigidly thereto and extending forwardly therefrom, a wheeled 75 truck connected thereto between the tongues and adapted to give support to the tongues to relieve the neck weight on the animals when the machine is in operation, the said truck being movable up and down relatively 80 to the tongues and frame, and means for controlling the up and down movements of said truck.

In testimony whereof I affix my signature in presence of two witnesses.

ALEXUS C. LINDGREN.
